(57) **CLAIM**

The ornamental design for a tool rack, as shown and described.

DESCRIPTION

FIG. 1 is a perspective view of the tool rack;

FIG. 2 is a right side view of the tool rack, the left side being a mirror image thereof;

FIG. 3 is a top view of the tool rack;

FIG. 4 is a bottom view of the tool rack;

FIG. 5 is a front view of the tool rack; and,

FIG. 6 is a rear view of the tool rack.

The broken lines in the drawings illustrate portions of the tool rack which form no part of the claimed design.
